UNITED STATES PATENT OFFICE.

ALPHONS LEMKE, OF ASCHAFFENBURG, BAVARIA.

LOCK.

SPECIFICATION forming part of Letters Patent No. 234,592, dated November 16, 1880.

Application filed November 20, 1877. Patented in France September 11, 1877, in Italy October 25, 1877, in England September 17, 1877, and in Germany August 26, 1877.

To all whom it may concern:

Be it known that I, ALPHONS LEMKE, of Aschaffenburg, in the Kingdom of Bavaria, German Empire, have invented certain Improvements in Door-Locks, of which the following is a specification.

The present invention has reference to that class of locks in which the opening operation is effected by electro-magnetism or air-pressure; and the invention consists in the construction and combination of parts which will be hereinafter more fully explained and claimed, so as to enable others skilled in the art to make and use the same.

15 In the accompanying drawings, forming part of this specification, Figures 1 and 2 are face views of a lock having electro-magnets and armature, and representing the latch-bolt, respectively, in a projected and retracted position. Figs. 3 and 4 are similar views, showing a modification in which a flexible air bulb or sack is used for opening the lock.

As shown in Figs. 1 to 4, inclusive, the sliding latch-bolt A is retracted or drawn back 25 into the lock-casing by means of a double-armed or centrally-pivoted lever, B, having its lower arm connected with a coiled spring, C, which serves to throw the lower arm of the lever to the left and the upper arm to the 30 right for projecting the latch-bolt into the door-frame or lock-strike.

When the bolt A is in a projected position the lower arm of the lever B engages with the hub D of a trigger, d, said hub being 35 provided with a locking shoulder or projection, b, for this purpose. The upper end of the lever is retained by means of a double-armed lever, F F', the arm F' of which serves as an armature, which is attracted by the electro-magnets when the electric current is passing through the same.

The movement of the armature-lever is regulated or defined by means of a set-screw, f, and a spring, g, serves to withdraw it from the 45 magnets.

As shown in Fig. 1, the lock is represented in a locked position. In order to retract the bolt a current of electricity is made to p-

through the magnets, which then attract the armature F', and the arm F is released from engagement with the trigger-arm d. Consequently the spring C operates the lever B and throws the latch-bolt back, also throwing forward at the same time a second bolt, K, having an inclined nose or front face, said bolt serving to open the door. This result is effected by causing the said bolt K, as it is thrown forward, to engage with an inclined projection, k, of the lock-strike, or a plate applied to the door-frame.

The bolt K also has for its object to set the mechanism when the door is shut. As the bolt K strikes the door-frame or lock-strike the spring-tongue i of said bolt bears against the projection i' of the lever B and presses 65 the same back, so as to cause its lower end to engage with the shouldered hub D of the trigger-arm d. This operation will cause said trigger to engage with the armature or locking-lever F F', for maintaining the latch-bolt 70 A in a projected position. A coiled spring, K², having an arm, serves to throw the bolt K forward when it is released from the lever mechanism.

The latch-bolt can also be operated independently of the mechanism heretofore described by means of a lever, M, and an elbow-arm, L. The former is moved by the key, which serves to operate the ordinary lock-bolt, and the elbow-arm is connected with the ordinary 80 knob-spindle.

Instead of the electro-magnets and armature, I also propose to use a flexible air bulb or bag, H, which is applied to a supporting-plate carrying a spring-pressed lever, F². The 85 latter engages with the trigger-arm in the same manner and for the same purpose as the armature-lever.

The air-bag, when inflated by means of a suitable air-tube, will serve to turn the lever 90 F², thus releasing the trigger and the lever mechanism from the latch-bolt and throwing the same back.

Having thus described my invention, what I claim as new, and desire to secure by Letters Patent, is—

The pivoted lever B, having projection *v*,
spring C, trigger *d*, provided with hub D and
shoulder *b*, and double-armed lever for lock-
ing and releasing the trigger, in combination
5 with electro-magnets or an equivalent releasing
device, latch-bolt A, and bolt K, substantially
as herein set forth.

In testimony whereof I have signed my
name to this specification in the presence of
two subscribing witnesses.

ALPHONS LEMKE.
